PORTABLE TABLE AND CARRIER

George B. Wisecarver, Pikeville, Ky.

Application November 14, 1941, Serial No. 419,179

3 Claims. (Cl. 211—126)

This invention relates to a wheeled portable table in the form of a carrier, and its general object is to provide a device of that character which can be utilized for any suitable purpose, but is very satisfactory for use in restaurants and the like, particularly as a carrier for collecting soiled dishes, silverware, etc. from tables and transporting the same to a washing room, in that the device includes dish receiving receptacles that are held relative to the device against casual removal or displacement and by ring members which also act as shock absorbing means and bumpers to protect the dishes, as well as to prevent the device from damaging furniture when moved from place to place.

A further object is to provide a portable table in which the ring members above mentioned are preferably discarded pneumatic vehicle tire casings, and which are associated and secured to the legs of the device in a unique manner.

Another object is to provide a portable table that can be moved from place to place with minimum effort on the part of the user, and the device is simple in construction, inexpensive to manufacture, and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a top plan view of the device.

Figure 2 is a side view thereof, partially in vertical section.

Figure 3 is a sectional view taken approximately on line 3—3 of Figure 2, looking in the direction of the arrows.

Referring to the drawing in detail, it will be noted that my device includes four leg members 1, in the form shown, but any suitable number may be provided, and the leg members are of a height substantially coextensive with that of the device, as well as are supported by casters 2. The legs are shown as being of cross sectional square cornered form and mounted on the upper portions of the legs is an upper ring member 3 which together with the lower ring member 4 that is mounted on the legs interme-

diate their ends, act to fix the legs in place and in equidistantly spaced relation to each other.

Each of the ring members is preferably a discarded vehicle tire casing, as will be apparent from Figure 2 of the drawing, therefore the ring members are made from fabric reinforced elastic material and are hollow as well as are transversely rounded from the open inner sides thereof. The ring members are arranged horizontally and of course have their open sides innermost and include upper and lower side walls 5 and 6 respectively. The lower side of the upper ring member is slit at intervals about the circumference thereof, and the leg members extend through the slits so that the inner face of the upper side wall rest upon the upper ends of the leg members, the said upper ends being rounded to follow the shape of the said inner face, as clearly shown in Figure 2. The material of the ring members upon opposite sides of the slits is directed outwardly relative to the interior of the ring member to provide substantially arcuate elongated flanges 7 and 8 respectively, that bear against the inner and outer faces of the leg members. The inner flanges 7 are of greater width than the outer flanges 8 and are secured to the leg members by suitable fastening means, such as screws 9.

Both the upper and lower side walls of the lower ring member 4 are slit at intervals, as at 10, about the circumference thereof, with the companion slits arranged in registration, and the leg members extend through the slits 10, as best shown in Figure 2. The material upon opposite sides of the slits 10 is also outwardly directed relative to the interior of the ring member 4, to provide substantially arcuate elongated flanges bearing against the inner and outer faces of the leg members, and the outer flanges 11 of the upper side wall are fixed to the outer faces of the leg members by screws 12, while the inner flanges 13 are fixed to the inner side faces of the leg members by screws 14, and it will be noted that the flanges 11 and 13 are of greater width than the flanges 7 and 8 respectively, so that ample material is provided to receive the screws for securing the flanges to the leg members, thus assuring that the ring member will be held fixed to the leg members against any possibility of casual displacement.

The inner annular edges of the upper walls of each of the ring members are beaded as at 15. In fact, the usual wheel rim receiving beads are retained on the ring members in the form shown, the latter being tire casings as previously set

forth, and the beads 15 provide seats for receiving the outwardly directed annular flanges 16 about the upper ends of pan like receptacles 17, the flanges resting upon the beads for disposal of the receptacles in depending relation within the inner sides of the ring members, and the receptacles are of a depth to extend below the open portions of the inner sides, as shown in Figure 2. By that construction, it will be obvious that the receptacles can be readily applied and removed with respect to the ring members.

Handles 18 are secured to the upper side walls of the upper ring member for disposal diametrically opposite each other, the handles extending at an outward inclination, and are of the inverted U-type, with apertured ears 19 on the limbs thereof, for receiving securing means 20. The handles are of course to facilitate removing the device from place to place.

While my device may be used for any suitable purpose, it is exceptionally useful in restaurants and the like, and particularly cafeterias, for collecting soiled dishes, etc. from tables, as previously set forth, it being understood that the device can be wheeled from table to table and the dishes are removed from the tables and placed within the receptacles 17, to be ultimately transported to a washing room or kitchen, thus it will be seen that my device eliminates the burdensome task of carrying the dishes on a tray. However, my device may be equipped with trays 21. When the device is not in use, one of the trays is disposed in inverted position upon the upper ring member and the other is disposed accordingly within the lower receptacle, as shown in Figure 2.

In view of the fact that the ring members are of elastic material, and the rounded outer sides thereof project laterally of the leg members, it will be obvious that the ring members also act as cushioning means or bumpers to prevent the device from damaging furniture and the ring members likewise act as shock absorbing means to prevent breakage of dishes within the receptacles.

When the device is not used as a dish collector, and with the upper tray in place as shown, the device can then be used as a table for supporting articles, as will be apparent.

It is thought from the foregoing description that the advantages and novel features of the invention will be readily apparent.

It is to be understood that changes may be made in the construction and in the combination and arrangement of the several parts, pro-

vided that such changes fall within the scope of the appended claims.

What I claim is:

1. A device of the character described comprising upright leg members, upper and lower ring members fixed to the leg members for holding the latter in place, said upper ring member being hollow and including upper and lower side walls, the lower wall being slit at intervals about the circumference thereof, the upper portions of the leg members extending through the slits and the inner face of the upper wall resting upon the upper ends of the leg members, and flanges formed along the length of each slit and certain of the flanges being fixed to the leg members.

2. A device of the character described comprising leg members, upper and lower horizontally arranged superimposed reinforced elastic ring members having upper and lower side walls, the upper ring member being fixed to the upper end portions of the leg members and the lower ring member being fixed to the leg members intermediate the ends thereof for the ring members to hold the leg members in place and for the legs to support the ring members, and annular beads extending inwardly from the side walls of the ring members.

3. A device of the character described comprising wheeled supported upright leg members, upper and lower hollow reinforced elastic ring members having open inner sides, rounded outer sides and upper and lower side walls, the upper ring member having its lower wall slit at intervals about the circumference thereof, said leg members having their upper portions extending through the slits and the inner face of the upper wall resting upon the upper ends of the leg members, depending flanges formed along the length of the slits and bearing against the leg members, certain of the flanges being fixed to the leg members, the lower ring member having its upper and lower walls slit at intervals about the circumference thereof, with the slits arranged in pairs, and the slits of each pair registering with each other, said leg members extending through the registering slits, and flanges formed along the length of the registering slits and rising from the upper slits and depending from the lower slits, certain of the slits of the lower ring member being fixed to the leg members, said slits being arranged for disposing the rounded sides of the ring members outwardly beyond the leg members for the ring members to act as bumpers for the device.

GEORGE B. WISECARVER.
